[57] ABSTRACT

An attenuator for a wide range of frequencies has a dielectric plate supported within first and second outer-conductors. A rectangular resistive member is deposited on the surface of the dielectric plate and is contiguously interposed between two pairs of highly conductive electrodes. An impedance compensation member having substantially the same shape as the rectangular resistive member is deposited on either the inner surface of the first outer-conductor or the second outer-conductor so as to at least compensate for variation of the characteristic impedance produced when a high frequency current flows in the electrodes.

ATTENUATOR FOR A WIDE RANGE OF FREQUENCIES

BACKGROUND OF THE INVENTION

1. Field of the Invention

This invention relates in general to an attenuator for a wide range of frequencies and more particularly to attenuators with extremely little variation in characteristic impedance and in attenuation over the wide frequency range.

2. Description of the Prior Art

U.S. Pat. No. 3,227,975 is exemplary of prior art attenuators and discloses a distributed network resistive film attenuator.

This invention provides for an attenuator which is based on the attenuator of the above-mentioned patent and which improves the defects which result from the conventional attenuator.

It is generally known from electromagnetic theory that the lines of magnetic force or of electric force distort due to the discontinuity of an inductivity and permeability. Thus, for example, in the conventional distributed network resistive film attenuator a resistive film is provided contiguously interposed between a pair of highly conductive electrodes so that when current high frequency flows in the highly conductive electrodes the lines of electric force distort.

Accordingly, the conventional attenuator as shown in FIG. 1 having the same principle of operation as the attenuator disclosed in the above-mentioned patent has certain defects in that when a current I_1 at a microwave frequency flows in highly conductive electrodes 5a, 5b, the characteristic impedance Z_0 varies and a variation in attenuation occurs wherein a load having an impedance Z_0 equal to the characteristic impedance Z_0 is connected between the electrode 5b and an outer-conductor 2 as shown in FIG. 2. For this reason, where the current I_1 flows in highly conductive electrodes 5a, 5b, lines of electric force are generated perpendicular to the electrodes 5a, 5b, and reach the inner surface of outer-conductors 1, 2. On the other hand where the current I_1 flows in a resistive member contiguously interposed between a pair of electrodes 5a, 5b, then the lines of electric force reach the inner surfaces of the outer-conductors 1, 2 causing the distortion line as shown in FIG. 2, wherein ϕ_1 , ϕ_2 , ϕ_3 and ϕ_4 designate emission angles respectively and 4 designates a dielectric plate. The length of the lines of electric force from a resistive member 6a to the inner surfaces of the outer conductors 1, 2 is longer than the lines of electric force from the electrodes 5a, 5b to the inner surfaces of the outer-conductors 1, 2. As a result thereof when a current having a high frequency flows in the electrodes 5a, 5b then the frequency sensitivity of VSWR representing variation in the characteristic impedance Z_0 is large so as to result in reflection of current at high frequencies and variation in attenuation.

SUMMARY OF THE INVENTION

Accordingly, it is an object of this invention to provide a new and improved unique wideband attenuator, for example in the range of D.C. to 18GHz.

It is still another object of this invention to provide a new and improved unique attenuator which minimizes variation in characteristic impedance so as to provide a substantially constant attenuation with high frequency.

Briefly, in accordance with this invention, the foregoing and other objects are provided by an attenuator which includes a dielectric plate supported within first and second outer-conductors. A rectangular resistive member is deposited on the surface of the dielectric plate and contiguously interposed between two pairs of highly conductive electrodes. An impedance compensation member having substantially the same shape as the rectangular resistive member is deposited on at least either the inner surface of the first conductor or the second outer-conductor so as to compensate for variation in characteristic impedance Z_0 produced when a high frequency current flows in the highly conductive electrodes.

BRIEF DESCRIPTION OF THE DRAWING

Other objects and features of the invention will become apparent to those skilled in the art as the disclosure is made in the following description of preferred embodiments of the invention, as illustrated in the accompanying sheets of drawings, in which like reference characters designate the same or similar parts throughout the several figures thereof and wherein;

FIG. 1 shows a cutaway view, partly in section, of a conventional attenuator.

FIG. 2 illustrates a side and cutaway view of the attenuator shown in FIG. 1.

FIG. 3 shows a perspective view and a cutaway view, partly in section, of a first preferred embodiment of the invention.

FIG. 4 and FIG. 5 are front and side views of the attenuator shown in FIG. 3 respectively.

FIG. 6 shows a perspective and a cutaway view, partly in section, of a second preferred embodiment of the invention.

FIG. 7 and FIG. 8 are front and side views of the attenuator shown in FIG. 6 respectively. FIG. 9 illustrates a perspective view and a cutaway view, partly in section, of a third preferred embodiment of the invention.

FIG. 10 and FIG. 11 are front and side views of the attenuator shown in FIG. 9 respectively.

FIG. 12 shows a perspective view and a cutaway view, partly in section, of a fourth preferred embodiment of the invention.

FIG. 13 and FIG. 14 are front and side views of the attenuator shown in FIG. 12 respectively.

FIG. 15 and FIG. 16 show perspective views and cutaway views, partly in section, of fifth and sixth preferred embodiments of the invention respectively.

FIG. 17 shows a front view of a seventh preferred embodiment of the invention.

DETAILED DESCRIPTION OF THE PREFERRED EMBODIMENTS

A first preferred embodiment of the invention will be explained by referring to the drawings of FIG. 3, FIG. 4 and FIG. 5. The first embodiment shows a bi-directional attenuator.

The numerals 1 and 2 designate a first and a second outer conductor respectively, both of which are provided with U shaped grooves. A set of the first and second outer conductors 1, 2 forms a hollow conductor 3. The lengthwise upper edges of the inner wall sides of the first and second outer conductors 1, 2 are provided with an L shaped notch, a set of which forms L shaped grooves. A dielectric plate 4 is in the L shaped grooves so as to be supported by the grooves. A rectangular re-

sistive member 6a is deposited on the surface of the dielectric plate 4 by sputtering techniques and the like which are well known in the art and contiguously interposed between third conductors 5a, 5b and fourth conductors 7, 8. The third conductors 5a, 5b are highly conductive electrodes and are provided on a central portion of the dielectric plate 4 through the rectangular resistive member 6a. The fourth conductors 7, 8 are disposed between the outer conductors 1, 2 and the lengthwise edges of the rectangular resistive member 6a along the full length thereof so as to provide electrical signal connections. The entire area of the rectangular resistive member 6a is made to have equal values of resistance.

First and second impedance compensation members 9a, 10a having substantially the same shape as the first rectangular member 6a are deposited on the inner surfaces of the first and second conductors 1, 2 respectively and are positioned above and under the rectangular resistive member 6a so as to compensate for variation in characteristic impedance Z_0 produced when a high frequency current flows in the electrode 5a, 5b. The impedance compensation members 9a, 10a may be made from conductive members of brass and the like and may be about 0.32 mm in thickness.

As shown in FIG. 4 one of both side edges of the impedance compensation members 9a, 10a are deposited on a first position A or a second position A' of the inner surfaces of the first and second outer-conductors 1, 2 such that the lines of electric force radiated from boundary B or B' of the electrode 5a or 5b and the rectangular resistive member 6a will reach the same when a high frequency current I_2 or I'_2 flows in the electrode 5b. As shown in FIG. 5, the width of the impedance compensation members 9a, 10a are designed to be longer than the width W_1 of the rectangular resistive member 6a. The above-mentioned positions A and A' are generally obtained by a conventional means of drawing figures based on emission angles ϕ_1, ϕ_2, ϕ_3 and ϕ_4 and the like or calculation of the lines of electric force.

As shown in FIG. 4, when a current I_2 or I'_2 having a high frequency flows in the third conductors 5a, 5b, then the lines of electric force will radiate from the third conductors 5a, 5b or the rectangular resistive member 6a as shown in the drawing by a dotted line curve. The thickness of the impedance compensation members 9a, 10a are designed so that the distance of the radiated electric force lines from the third conductors 5a, 5b to the inner surfaces of the first and second conductors 1, 2 is equal to the distance of the radiated electric force lines from the rectangular resistive member 6a to the impedance compensation members 9a, 10a.

As a result thereof variation in characteristic impedance Z_0 is drastically minimized and the line having the characteristic impedance Z_0 includes the third conductors 5a, 5b of width W_1 , the fourth conductors 7, 8 and the hollow conductor 3.

FIG. 6, FIG. 7 and FIG. 8 show a second preferred embodiment of the present invention. The embodiment of FIG. 6, FIG. 7 and FIG. 8 shows a bi-directional attenuator wherein the impedance compensation member 9b is deposited only on the first outer-conductor 1. In this case, the impedance compensation member 9b is designed to be thicker than the impedance compensation members 9a, 10a of the attenuator as shown in

FIG. 3 since the impedance match is not as good as that of the embodiment of FIG. 3.

FIG. 9, FIG. 10 and FIG. 11 show a third preferred embodiment of the present invention. The embodiment of FIG. 9, FIG. 10 and FIG. 11 shows a bi-directional attenuator wherein the impedance compensation member 10b is deposited only on the second outer-conductor 2. The impedance compensation member 10b is designed to be thicker than the impedance compensation members 9a, 10a of FIG. 3 like in the embodiment of FIG. 6, FIG. 7 and FIG. 8.

FIG. 12, FIG. 13 and FIG. 14 show a fourth preferred embodiment of this invention. This embodiment is a bi-directional attenuator. As shown in FIG. 12, FIG. 13 and FIG. 14 a rectangular resistive member 6b and third conductors 5a, 5b form a T shape-pattern. In this case, impedance compensation members 9c, 10c are deposited on the inner surfaces of the outer-conductor 1, 2 so as to be positioned above and under the rectangular resistive members 1, 2 respectively and so as to compensate for variation in the characteristic impedance produced when a high frequency current flows in the electrodes 5a, 5b.

FIG. 15 and FIG. 16 show bi-directional attenuators of a fifth and a sixth preferred embodiments of the present invention wherein impedance compensation members 9d or 10d are deposited either on the first outer-conductor 1 or on the second outer-conductor 2.

The embodiments of FIG. 15 and FIG. 16 have the same effect as the embodiment of FIG. 3, FIG. 4 and FIG. 5.

It should be understood that this invention is applicable to a single directional attenuator as well as a bi-directional attenuator. In this case, as shown by example in FIG. 17, the side edge of the impedance compensation members 9e and 10e having the same shape as the rectangular resistive member 6e are deposited on position A, A' of the inner surfaces of the first and second outer-conductors 1, 2 such that the lines of electric force radiated from boundary B or B' of the electrode 5a or 5b and the rectangular resistive member 6e will reach the same when a high frequency current I_2 flows in the electrode 5a.

As mentioned above, in accordance with this invention, it is apparent that variation in characteristic impedance and attenuation can be minimized over a wide frequency band.

Obviously, many modifications and variations of the present invention are possible in the light of the above teachings. It is therefore to be understood that within the scope of the appended claims the invention may be practiced otherwise than as specifically described.

What is claimed as new and desired to be covered by letters patent is:

1. An attenuator having upper and lower contiguous outer-conductors and a pair of coaxial inner conductors comprising:
  - a. a dielectric plate supported within said upper and lower outer conductors,
  - b. a first pair of electrodes connected to said upper and lower outer conductors,
  - c. a second pair of electrodes connected to said coaxial inner conductors,
  - d. a rectangular resistive member deposited on said dielectric plate and contiguously interposed between said first pair of electrodes and said second pair of electrodes, and

e. an impedance compensation member having substantially the same shape as said rectangular resistive member and deposited on at least either the inner surface of said upper outer-conductor or the inner surface of said lower conductor for compensating for variation in characteristic impedance.

2. An attenuator according to claim 1, wherein said impedance compensation member comprises a conductive member.

3. An attenuator to claim 1 wherein, both edges of the impedance compensation member are deposited at a position at least on either inner surface of the outer conductors such that lines of electric force radiated from the boundaries of the rectangular resistive member and the electrodes will respectively reach said compensation member.

4. An attenuator having upper and lower contiguous outer-conductors and a pair of coaxial inner conductors comprising:

- a. a dielectric plate supported within said upper and lower outer conductors,
- b. a first electrode connected to one of upper and lower said outer-conductors,

c. a second pair of electrodes connected to said coaxial inner conductors,

d. a rectangular resistive member deposited on said dielectric plate and contiguously interposed between said first electrode and said second pair of electrodes, wherein said resistive member and said second pair of electrodes form a T-shaped pattern, and

e. an impedance compensation member having substantially the same shape as said rectangular resistive member and deposited on at least either the inner surface of said upper outer-conductor or the inner surface of said lower outer-conductor for compensating for variation in characteristic impedance.

5. An attenuator according to claim 4 wherein, both edges of the impedance compensation member are deposited at a position at least on either inner surface of the outer conductors such that lines of electric force radiated from the boundaries of the rectangular resistive member and the electrodes will respectively reach said compensation member.
